UNITED STATES PATENT OFFICE.

ALGY J. SMITH, OF SWISSVALE, PENNSYLVANIA, ASSIGNOR TO HARTFORD-EMPIRE COMPANY, OF HARTFORD, CONNECTICUT, A CORPORATION OF DELAWARE.

TIMER.

Application filed January 13, 1926, Serial No. 81,113. Renewed November 13, 1926.

This invention relates to timers and more particularly to apparatus known in the trade as motor driven timers, an object of the invention being to provide an apparatus of this character which will automatically control the time of opening of valves and is particularly adapted for use in the glass-making trade, although I would have it distinctly understood that I desire to cover the apparatus broadly for any use to which it can be put.

A further object is to provide a timer of the character stated which can be set so as to positively control the opening and closing movement of any desired number of valves, and I may accomplish this by providing rigidly held or normally stationary cam members which are capable of adjustment to position their cam faces so as to give the desired results.

A further object is to provide an apparatus of this character which can be manufactured and sold at a reasonably low price and which will most efficiently perform the functions for which it is intended.

A further object is to provide a timer apparatus wherein the adjustments to vary the timing are made on a normally stationary part or element, such for instance as the stationary cam. Thus the adjustments may be made conveniently and accurately while the timer is in operation.

With these and other objects in view, the invention consists in certain novel features of construction and combinations and arrangements of parts, which will be more fully hereinafter described and pointed out in the claims.

In the accompanying drawings—

Figure 1 is a view in longitudinal section illustrating my improved timer.

Figure 2 is a view in vertical transverse section on the line 2—2 of Figure 1, the view being on an enlarged scale;

Figure 3 is a similar view in section on the line 3—3 of Figure 1;

Figure 4 is a similar view in section on the line 4—4 of Figure 1;

Figures 5 and 6 are views in section, at right angles to each other, illustrating a modification in which Woodruff keys are employed instead of the single key shown in Figure 3;

Figure 7 is a view similar to Figure 1, illustrating a modification;

Figure 8 is a view in vertical transverse section on an enlarged scale on the line 8—8 of Figure 7;

Figure 9 is a similar view in section on the line 9—9 of Figure 7;

Figure 10 is a similar view in section on the line 10—10 of Figure 7.

Referring more particularly to Figures 1 to 4, inclusive, 1 represents a base on which a series of valves 2, 3 and 4 are mounted. 65 These reference characters 2, 3 and 4 are employed to designate the valve as a whole, although only the casings of such valves are shown, said valves being opened and closed through the medium of crank arms 5, 6 and 7, respectively, connected to the respective valves, as clearly shown in Figure 1. These valves may control the flow of air or any other fluid, and while I have illustrated three of such valves it is obvious that any 75 desired number may be employed with the corresponding number of operating mechanisms, such as will be hereinafter described in connection with the three valves.

A series of bearing brackets 8 are fixed 80 to the base 1 and provide mounting for a plurality of nested shafts, the inner shaft 9 constituting a solid shaft and the other shafts 10, 11 and 12 constituting tubular shafts of graduated increasing diameter 85 loosely fitting one upon the other and adapted to move relatively to each other, as will be more fully hereinafter described.

The inner or solid shaft 9 also has a mounting in a bearing 13 and carries a worm 90 wheel 14 which is driven by a worm 15 on a shaft 16. This shaft 16 also has a disk 17 fixed thereon which is driven by a friction pinion 18 on the drive shaft 19 of an electric or other motor 20.

As illustrated in Figures 1 and 3, a single key 21 is projected through the solid shaft 9 and through longitudinal slots 22 in the tubular shafts 10, 11 and 12 so as to compel all of the shafts to revolve together but permitting independent longitudinal movement of the several tubular shafts.

In the modification illustrated in Figures 5 and 6, instead of employing a single key 21 I employ what is known in the trade as Woodruff keys 23, projecting through slots 24 in the respective shafts 10, 11 and 12, and into recesses 25 in the solid shaft 9. These keys are held in place by a ring 26 having adjusting screws 26^a therein to en- 110

gage the keys 23 and hold them securely in place.

With either form of key construction the same result is accomplished, namely, that all of the shafts are compelled to revolve or turn together while each of the tubular shafts is capable of independent longitudinal movement.

The shafts 10, 11 and 12 have fixed thereon 20 annularly grooved collars 27, and these collars are preferably split, as shown in Figure 4, the split portion being bridged by an adjusting screw 28 to securely clamp them on the shafts. These collars engage rollers 29 on the respective crank arms 5, 6 and 7 so that when the collars are moved longitudinally the crank shafts are moved to open and close the valves, as will more fully hereinafter appear.

20 The base 1 supports a longitudinal series of vertically disposed uprights 30, the upper portion of said uprights being circular in form and constituting rigidly mounted disks, and for convenience of description I shall 25 give these several disks separate reference characters. Beginning with the left of Figure 1, these disks I number in order 31, 32, 33 and 34.

Between each pair of disks I provide two 30 cam members 35 and 36. As each pair of cam members is precisely alike except the diameter of hole in centre, the description hereinafter of one pair will apply alike to all.

35 The cam members 35 and 36 are circular and of disk-like form and are mounted to turn freely on bushings supporting the respective shafts but are held against movement by means of spring catches 37, said 40 catches having pins 38 adapted to be projected through registering openings 39 in the cam members and in the stationary disks as illustrated in Figure 1. In other words, each stationary disk has a circular series of 45 openings 39, in any of which the catch pin 38 may be located to properly position the cam member.

These cam members preferably have annular flanges 40 opposing each other and 50 meeting so as to form an enclosure or encasement, and in each of said enclosures or encasements a crank arm is mounted. There are three of these crank arms shown to which I have given reference numerals 41, 55 42 and 43, respectively. The crank arm 41 is fixed to the tubular shaft 16; the crank arm 42 is fixed to the tubular shaft 11; and the crank arm 43 is fixed to the tubular shaft 12. These arms 41, 42 and 43 carry 60 rollers 44 at their free ends, and said rollers are adapted to engage cams 45 on the respective cam members which will cause their respective shafts to be moved longitudinally to positively move the valves to open and closed positions.

It will be noted that these cams 45 on the respective pairs of cam members function to positively move the arms first in one direction and then in the other direction, and, as these cam members are capable of an 70 annular adjustment to position the cams as may be desired to time the opening and the closing of the valves, it is also possible that through manual error these cams may be opposed directly to each other which would 75 cause the arms or some other part of the mechanism to be broken, and to prevent this possibility I provide on the outside of each cam member laterally projecting lugs or 80 stops 46 which will strike each other and prevent possibility of the cams being located directly opposite to each other.

The operation of this form of my invention will be apparent. As all of the shafts are continuously revolved at the desired 85 speed in accordance with the position of the friction pinion 18 on the face of the disk 17 all of the crank arms 41, 42 and 43 will likewise turn with their shafts, and as the rollers 44 on said arms engage the cams 45 90 the respective shafts will be caused to move longitudinally and this longitudinal movement of the shafts will cause the opening and closing of the valves as above explained.

The timing of the said movement of the 95 valves is regulated by the positions of the respective cams and as said cams are mounted on members capable of adjustment the operation can be arranged to suit any condition.

100 In the modification illustrated in Figures 7 to 10, inclusive, I provide a base 1, motor 20, shaft 19, friction pinion 18, friction disk 17, worm 15, shaft 16, and worm wheel 14 similar to that shown in the form above described.

105 In this modification I have illustrated but two valves 47 and 48 although of course it is to be understood that any desired number of valves with corresponding operating 110 mechanism may be provided.

115 In this modification four tubular nested shafts 50, 51, 52 and 53 are provided, said series of shafts being supported in suitable bearing brackets 54 and 55. The bearing brackets 55 have bearings 56 in which the hubs 57 of a cam casing 58 are mounted to turn, and this cam casing is fixed to turn with the solid shaft 49 which is driven by the worm wheel 14. This cam casing 58 may be 120 made up of any desired number of sections secured together by bolts 59, and said sections are capable of adjustment relative to each other to properly position cams 60 therein relative to each other.

125 Said shafts 50, 51, 52 and 53 are provided, respectively, with crank arms 61, 62, 63 and 64 within the cam casing 58, and these crank arms 61, 62, 63 and 64 are rigidly fixed to their respective shafts and carry rollers 64' 130

at their free ends to engage the cams 60. As in the other form, these cams are so arranged at opposite sides of the crank arms as to positively move said crank arms in the opposite direction to cause the respective pairs of shafts to be moved longitudinally in opposite directions.

One of the main differences between this modification and the preferred form is that in this modification the tubular shafts do not revolve but are caused to move longitudinally by the engagement of the cams in the rotary cam casing with the crank arms 61, 62, 63, 64, respectively.

The valves 47 and 48 have crank arms 65 thereon, said crank arms having rollers 66 at their free ends engaged by collars 67 and 68, respectively. These collars 67 and 68 are secured to their respective shafts by jam screws 69 so as to hold them at any annular adjustment on their respective shafts.

One pair of collars 67 and 68 is mounted on shafts 51 and 50, respectively, and is positioned close together. The other pair of collars 67 and 68 is mounted on shafts 53 and 52, respectively, and is shown positioned close together as it should be, but it is to be understood that each member of each pair is movable annularly with its respective mate to make proper adjustment and swing the crank arms 65 of the respective valves in opposite directions.

To prevent rotary movement of these collars, each collar is formed with an annularly notched flange 70, and pivoted dogs 71 mounted on fixed parts of the apparatus rest by gravity or springs in the notches but are capable of being swung out of the notches to allow the collars to be turned by handles 72 fixed to the collars.

The reason for permitting adjustment of the collars annularly is to manually move the crank arms as it is to be understood that these collar members are fixed to their respective shafts, and the turning of a collar member causes a corresponding turning movement of the shaft and its operating crank arm so as to vary the positions of said crank arms relative to the cams and give the desired time of positive movement to the respective valves. As it is possible to move these cam operated arms so that they might be broken if alined, or if the cams are alined, I have provided, on said collars, stops 73 which will strike each other and prevent the possibility of the turning movement of the collars to a position which would cause damage to the apparatus.

In the operation of this modified form of device, the cam casing 58 is revolved and the respective cams 60 therein engage the arms 61, 62, 63 and 64, respectively, to cause the several pairs of shafts 50, 51 and 52, 53 to be moved longitudinally or reciprocated in op-

posite directions, and the movement of these shafts through the medium of their respective collars imparts a positive movement to the crank arms 65 to open and close the valves at the proper time.

It will thus be noted that with both forms of apparatus above illustrated I may adjust the parts so as to synchronize the opening of any number of valves, switches or any other apparatus, and while I shall refer to the operated means as "valves" it is to be understood that I do not limit myself in this particular.

The cam or crank arms can be adjusted so that the time of operation of any valve or any number of valves may be regulated either as regards the opening or closing of the valve and the time of opening, and, furthermore, this operation of adjustment may take place while the machine is in operation regardless of the speed of the machine. Furthermore, the apparatus is capable of a wide range of utility and therefore I do not limit myself to any particular use.

Various slight changes and alterations might be made in the general form of the parts described without departing from my invention and hence I do not limit myself to the precise details set forth but consider myself at liberty to make such slight changes and alterations as fairly fall within the spirit and scope of the appended claims.

I claim:

1. A machine of the class described, including a plurality of nested shafts, means operatively connecting said shafts with a part to be moved, and means for imparting independent movement to a shaft, said shafts keyed to turn together but capable independently of longitudinal movement.

2. A machine of the class described, including a plurality of nested shafts, means operatively connecting said shafts with a part to be moved, and means for imparting independent movement to a shaft, said means imparting positive movement to the shafts in both directions, said shafts keyed to turn together but capable independently of longitudinal movement.

3. A machine of the character described, including a plurality of nested shafts, valve engaging means operatively connected to the respective shafts, and cams imparting longitudinal movement to said shafts to open and close the valves, said movement being positive in both directions.

4. A machine of the class described, including a plurality of nested tubular shafts, means operatively connecting said shafts with a part to be moved, means for imparting independent movement to a shaft, a motor driven shaft within the nested shafts and imparting continuous rotary motion thereto, and adjustable means controlling the

longitudinal movements of the shafts for timing the movement of any shaft in either or both directions.

5. A machine of the class described, including a plurality of nested tubular shafts, means operatively connecting said shafts with a part to be moved, means for imparting independent movement to a shaft, said means imparting positive movement to the 10 shafts in both directions, a motor driven shaft within the nested shafts imparting continuous rotary motion thereto, and adjustable means controlling the longitudinal movements of the shafts for timing the 15 movement of any shaft in either or both directions.

6. A machine of the class described, including a plurality of nested tubular shafts, means operatively connecting said shafts 20 with a part to be moved, means for imparting independent movement to a shaft, said shafts keyed to turn together but capable independently of longitudinal movement, a motor driven shaft within the nested shafts 25 and imparting continuous rotary motion thereto, and adjustable means controlling the longitudinal movements of the shafts for timing the movement of any shaft in either or both directions.

30 7. A machine of the class described, including a plurality of nested tubular shafts, means operatively connecting said shafts with a part to be moved, means for imparting independent movement to a shaft, said 35 means imparting positive movement to the shafts in both directions, said shafts keyed to turn together but capable independently of longitudinal movement, a motor driven shaft within the nested shafts and imparting 40 continuous rotary motion thereto, and adjustable means controlling the longitudinal movements of the shafts for timing the movement of any shaft in either or both directions.

45 8. A machine of the character described, including a plurality of nested tubular shafts, valve engaging means operatively connected to the respective shafts, cams imparting longitudinal movement to said 50 shafts to open and close the valves, a motor driven shaft within the nested shafts and imparting continuous rotary motion thereto, and adjustable means controlling the 55 movements of the shafts for timing the movement of any shaft in either or both directions whereby the time of movement and the time of remaining open of each valve can be controlled.

60 9. A machine of the character described, including a plurality of nested tubular shafts, valve engaging means operatively connected to the respective shafts, cams imparting longitudinal movement to said 65 shafts to open and close the valves, said movement being positive in both directions,

a motor driven shaft within the nested shafts and imparting continuous rotary motion thereto, and adjustable means controlling the longitudinal movements of the shafts for timing the movement of any shaft 70 in either or both directions whereby the time of movement and the time of remaining open of each valve can be controlled.

10. A machine of the character described, including a plurality of nested shafts, valve 75 operating means connected to the respective shafts, cam members concentric with the shafts and having cams thereon, said members adapted to be adjusted around the shafts to position the cams at points desired, means 80 for locking said cam members against movement after adjustment, and arms fixed to the respective shafts and engaging the cam members.

11. A machine of the character described, 85 including a plurality of nested shafts, valve operating means connected to the respective shafts, cam members concentric with the shafts and having cams thereon, said members 90 adapted to be adjusted around the shafts to position the cams at the points desired, means for locking said cam members against movement after adjustment, and arms fixed to the respective shafts and engaging the cam members, said cam members having annular flanges thereon and each pair of cam members 95 functioning as an enclosure for an arm.

12. A machine of the character described, 100 including a plurality of nested shafts, valve operating means connected to the respective shafts, cam members concentric with the shafts and having cams thereon, said members 105 adapted to be adjusted around the shafts to position the cams at the points desired, means for locking said cam members against movement after adjustment, arms fixed to the respective shafts and engaging the cam members, said cam members having annular 110 flanges thereon and each pair of cam members functioning as an enclosure for an arm, each cam member having a spring catch pin thereon, and fixed members having a circular series of openings therein to receive the pins and hold the cam members at any 115 position of adjustment, said parts constituting the cam member securing means.

13. A machine of the character described, including a plurality of nested shafts, fixed cam members, arms on the shafts engaging the cam members to independently move the shafts longitudinally and positively in both directions, grooved collars on the respective shafts, and valve crank arms engaging said 120 collars.

14. In timer mechanism, the combination of a plurality of stationary cams, a plurality of control elements each arranged to be actuated by one of the cams, means for moving said elements relative to their cams to effect 125

actuation, and means for adjusting the operative relation between each of the cams and the corresponding control element to independently vary the beginning and the ending 5 of the actuation of the control element by its cam.

15. In timing mechanism, the combination of a stationary cam, a control shaft mounted for both a rotary movement on its longitudinal axis and a longitudinal movement, means for rotating said shaft, connections whereby the longitudinal movements of the shaft effect the control operations, a member carried by said shaft and moved by engagement 10 with the cam to impart longitudinal movements to the shaft, and means for varying the time of occurrence of the control operation in a cycle of rotation of the control shaft including the adjustment of the operative 15 relation between the cam and the member.

16. In timing mechanism, the combination of a stationary cam, a control shaft mounted for both a rotary movement on its longitudinal axis and a longitudinal movement, means for rotating said shaft, connections whereby the longitudinal movements of the shaft effect the control operations, a member carried by said shaft and moved by engagement with the cam to impart longitudinal 20 movement to the shaft, and means for varying the time of occurrence of the control operation in a cycle of rotation of the control shaft including the adjustment of the cam.

17. In timer mechanism, the combination 25 of a plurality of parallel shafts mounted for both rotary and longitudinal movements, means for rotating said shafts, means whereby the longitudinal movements of said shafts effect the control operations, a plurality of stationary cams, a member carried by each 30 of said shafts and caused to move by engagement with one of said cams to impart longitudinal movement to its shaft, and means for adjusting the cam to vary the timing of the longitudinal movements of the shaft.

18. A mechanism for actuating a plurality 35 of valves, comprising a plurality of cams mounted on a common axis, connections between each cam and one of the valves, and means for causing a relative movement between each cam and its connections whereby the valve is actuated, said connections from one cam to its valve passing within the periphery of another cam.

19. A valve actuating mechanism comprising 40 a plurality of cams, a roll engaging each cam, said cams and rolls being mounted for movement about a common axis, means for rotating one of said members about the axis, means to permit the adjustment of the other member about the axis, and connections between one of the members and a valve whereby the valve will be actuated by the movement 45 of the member in the line of the axis.

20. In timer mechanism, the combination of a control member, a stationary cam comprising two sections in variable relation with each other, said sections being arranged to actuate the control member in opposite directions, and means to move the control member relative to the cam to effect actuation. 70

21. In timer mechanism, the combination of a control member, a stationary cam comprising two sections in variable relation with each other, said sections being arranged to actuate the control member in opposite directions, means to move the control member relative to the cam to effect actuation, and 75 means for adjusting one of the cam sections to vary the relation between the opposite actuations of the control member.

22. In timer mechanism, the combination of a shaft mounted for longitudinal movement, connections whereby the longitudinal movements of the shaft effect the control operations, a contact member associated with the shaft to effect longitudinal movements of the latter, a stationary cam comprising two sections, one of said sections being variable in relation to the other section, said sections being arranged to actuate the member to move the shaft longitudinally in opposite directions, and means to move the member in engagement with the sections to effect actuation. 85 90 95

23. In timer mechanism, the combination of a shaft mounted for longitudinal movement, connections whereby the longitudinal movements of the shaft effect the control operations, a contact member associated with the shaft to effect longitudinal movements of the latter, a stationary cam comprising two sections, said sections being arranged to actuate the member to move the shaft longitudinally in opposite directions, 100 105 means to move the member in engagement with the sections to effect actuation, and means for adjusting one of the cam sections to vary the relative timing of the opposite actuations of the member. 110

24. In timer mechanism, the combination of a plurality of shafts mounted for longitudinal movements and also rotary movements about their longitudinal axes, connections whereby the longitudinal movements of the shafts effect the several control operations, a contact member associated with each shaft and arranged to effect by its rotation longitudinal movements of the latter, a stationary cam for each contact member, said cam comprising two cam sections arranged to actuate the contact member in opposite directions, and means to rotate the 115 120 125 contact members to effect rotation.

25. In timer mechanism, the combination of a plurality of shafts mounted for longitudinal movements and also rotary movements about their longitudinal axes, connec- 130

tions whereby the longitudinal movements of the shafts effect the several control operations, a contact member associated with each shaft and arranged to effect by its rotation longitudinal movements of the latter, a stationary cam for each contact member, said cam comprising two cam sections arranged to actuate the contact member in opposite directions, means to rotate the contact members to effect rotation, and means for adjusting one of the cam sections to vary the relation between the opposite actuation of the corresponding contact member.

26. In timer mechanism, the combination of a pair of cam members mounted on a common support and having their adjacent faces provided with cam portions, a contact member movable between said cam members and actuated in opposite directions by said cam portions, and means for adjusting the relation between the cam members to vary the interval between opposite cam effects imparted to the contact member.

27. In timer mechanism, the combination of a plurality of parallel shafts mounted for

both rotary movement about a common axis and also for longitudinal movement, means for rotating said shafts, means whereby the longitudinal movements of said shafts effect the control operations, and a plurality of stationary cams, each of said shafts being operatively related to one of said cams so that the rotation of the shaft imparts longitudinal movement to the latter.

28. In timer mechanism, the combination of a plurality of parallel shafts mounted for both rotary movement about a common axis and also for longitudinal movement, means for rotating said shafts, means whereby the longitudinal movement of said shafts effects the control operations, a plurality of stationary cams, each of said shafts being operatively related to one of said cams so that the rotation of the shaft imparts longitudinal movement to the latter, and means for adjusting the relation between the cam and the shafts to vary the timing of the longitudinal movements of the shafts.

ALGY J. SMITH.
